KEY CONTAINER

George E. Gross, Chicago, Ill.

Application April 9, 1947, Serial No. 740,389

4 Claims. (Cl. 70—456)

1

This invention relates to a key container, and more particularly to a key container of especially simple construction from which keys are extruded and retracted by simple manipulation of a finger or thumb of one hand, preferably in conjunction with a spring.

Heretofore there has not been a key container on the market which has combined the advantages of spring operation with such simple construction that extremely low cost mass production is possible.

In accordance with my present invention, I provide a key container comprising a pair of identical key housing portions, each housing portion having a central longitudinal slot therein. A pair of studs having heads or buttons without the housing and shanks extending through the slots engage the holes in the key handles for manipulation thereof. Each housing portion preferably has a spring associated therewith for acting with and against the stud and only a single key therein.

The keys serve to hold each other in engagement with their respective studs so that the keys are freely removable upon separating the housing portions. At the same time, each key is individually and selectively extrudable from the housing for rapid and sure use.

It is therefore an important object of the present invention to provide a key container which represents the ultimate in a structure combining extreme simplicity and durability with facile and expeditious key manipulation.

It is a further important object of this invention to provide a key container which combines simple construction with simple rapid key removal and replacement.

It is a still further object of the invention to provide a key container which permits individual and selective extrusion and retraction of the keys for swift and sure use thereof.

Other and further objects of this invention will be apparent from the disclosures in the specification and accompanying drawings.

On the drawings:

Figure 1 is a perspective view of a key container embodying the principles of my present invention;

Figure 2 is a plan view of the bottom housing portion of my invention;

Figure 3 is a sectional view taken substantially along the line III—III of Figure 1;

Figure 4 is a longitudinal sectional view taken substantially along the line IV—IV of Figure 1 with parts partially in elevation;

2

Figure 5 is a sectional view taken substantially along the line V—V of Figure 4;

Figure 6 is a reduced plan view of the insert plate of my invention; and

Figure 7 is a side elevational view of the insert plate.

The key container or housing 10 of my invention comprises a pair of identical housing portions 11 and 12, preferably made of a suitable plastic. The upper and lower housing portions 11 and 12 are adapted to be held together by means of spring clips 13 and 14 on either side of the housing. Each housing portion has a slot at one end thereof, together forming an opening 15 in the housing. The opposite ends of the housing portions 11 and 12 may be curved as indicated by the reference numeral 16.

In the central portions of the upper and lower housing portions are cut longitudinal slots 17 and 18. As seen in Figures 3 and 4, studs 19 and 20 are slidably disposed in these slots indicated by reference numerals 17 and 18 and comprise a head or button 21 without the key housing and a shank 22 extending through the slot into the housing where a disk 23 is formed thereon to prevent displacement of the button 21 from the slot. A stud portion 24 extends from the shank 22 and is adapted to engage a hole 25 in the handle of a key 26. Referring to Figure 4, it will be seen that the two keys are positioned by means of flanges 27 of larger diameter than the key hole 25 in such a way that the opposed studs 24 cannot project through one key hole 25 to engage the second key in any manner. It will further be understood that each key serves to hold the other in engagement with its respective stud portion 24. Thus each key is individually extrudable from the housing 10 through the opening 15 therein for operation of a lock.

In the illustrated embodiment of my invention, a pair of springs 28 and 29 oppose the extrusion of the keys 26 and serve to retract the same after use. At one end, the springs 28 and 29 engage an intermediate shank portion 30 between the disk 23 and the flange 27 of the studs 19 and 20, and are slidably relative thereto as the spring is compressed. The forward ends of springs 28 and 29 engage in an upper slot (not shown) and a slot 31 in the lower housing portion 12 (Figure 2). A ledge 32 at the forward end of each housing portion serves to support the keys 26 between the adjacent springs 28 and 29 and the keys are therefore free from interference by the spring. The springs may, for example, be made of a music wire spring steel.

As illustrated in Figures 2 and 5, in addition to the spring clips 13 and 14 for securing the housing portions together, a tapered dowel hole 33 and tapered dowel pin 34 are formed on the respective side walls of each housing portion adjacent the open end thereof. These dowels serve to rapidly align the two housing portions and to prevent relative sliding thereof while the spring clips 13 and 14 prevent separation thereof. As best seen in Figure 2, the spring clips 13 and 14 engage with inwardly inclined recesses 35 on the housing portions 11 and 12 so that the spring clips 13 and 14 are held against sideways relative displacement with respect to the housing portions and are restrained against lateral disengagement and will lie substantially flush with the outer surfaces of the housing. For strength and also for ensuring that the keys will be extruded through the openings 15, the forward part of each housing portion preferably has a slanting wall portion 36 leading to the opening 15 which will serve to guide the forward portion of a key 26 along the angled surface thereof and through the opening 15.

In the illustrated embodiment of my invention, therefore, each key 26 is held in its retracted position by a spring 28 or 29 and is adapted to be moved manually forwardly by means of a stud 19 or 20 into the exposed position shown dotted in Figure 2. Bayonet portions 37 of the slot 17 and 38 of the slot 18 extend at right angles to the main slot portion and are adapted to hold the studs 19 or 20 in extruded position, in which position it will be understood that the key 26 is exposed for use.

If it is desired to employ my key case with shorter shanked keys, auxiliary forwardly extending slots 39 and 40 may be provided to accommodate either one or two smaller shanked keys.

The majority of keys which it might be desired to use in my container are of a substantially uniform thickness of nine-hundredths of an inch. However, if keys of materially less thickness are to be used, the auxiliary insert plate 41 shown in Figures 6 and 7 may be placed within the container. For this purpose recesses 42 and 43 are formed in the side walls of the housing portions as indicated in Figures 2, 3 and 4, each to receive one-half the thickness of the plate. The configuration of the plate 41 conforms to that of the housing portions and is of such length as to terminate just short of the dowel hole 33 and pin 34 of each housing so as not to interfere therewith. The thickness of the plate is such as to fit in the gap between the opposed stud portions 24 (Figure 3) and not interfere with movement thereof, at the same time eliminating any possibility of keys of less than the usual thickness becoming disengaged from the studs.

When the stud 19 or 20 is removed from its respective bayonet portion 37 or 38, either manually, directly, or by rotative movement of the housing while the key is in the lock, the spring 28 or 29 will serve to rapidly retract the key into the housing. Either stud 19 or 20 can, of course, operate independently of the other so that only the key which is to be used is extruded from the housing from manipulation in the lock. Even when one key is projected, the two keys co-operate to retain each other upon their respective studs. The key container is shown housing a pair of identically sized keys. However, of course, the container will operate effectively with different sized keys and dissimilar keys therein,

and the adjustments set forth above of providing auxiliary slots 39 and 40 and insert plate 41 may be made, if desired.

When a key is in the exposed position with its associated stud in the bayonet slot portion 37 or 38, the key is held substantially rigidly and may be directed toward the lock merely by directing the casing at the proper angle toward the lock. The bayonet slot portion can be as near the main slot portion as desired so that the key may be exposed from the casing exactly longitudinally thereof, the key handle opening 25 being of sufficient diameter to permit movement of the stud portion 24 therein without affecting the alignment of the key. After a key has been manipulated in the lock, in order to retract the key it is merely necessary to rock the casing slightly, thereby rotating the stud associated with the key out of its bayonet slot portion and into the main slot portion, whereupon the associated spring will serve rapidly to retract the key. Thus no handling of the key is necessary, but merely the manipulation of the button 21 of the stud associated with the key desired to be used by either a thumb or finger of one hand while said hand is grasping the key housing. The entire operation of extruding, locking or unlocking, and retracting may be readily accomplished with but one hand and without actual contact with the key to be used.

In assembling keys within the key housing, spring clips 13 and 14 are first removed and the housing portions separated. The two keys to be inserted may be simply aligned with a stud of one housing portion which is held horizontally as by laying the housing portion upon a flat horizontal surface with the stud portion projecting upwardly and then the second housing portion may be aligned therewith by means of the tapered dowel hole 33 and tapered dowel pin 34 of each housing portion. After the two housings are closed together, it is a simple matter to insert the spring clips on either side. If the auxiliary insert plate 41 is employed, a first key is placed on the upwardly projecting portion and the second key positioned on the second stud, also held in an upwardly projecting position. The plate 41 is then placed in position on one housing portion, and that portion inverted upon the other, the closed end of the inverted housing portion being engaged with the other housing portion first, to prevent the key from becoming disengaged from its stud.

These spring clips are preferably so constructed that they will require no effort to be clamped on either side of the housing portion. To accomplish this it will be noted that the edges of the recess 35 are preferably rounded as indicated at 44 in Figure 3. The spring legs 45 of the spring clips 13 and 14 preferably converge very slightly, for example, six-hundredths of an inch in three-tenths of an inch, so that very little expansion of the leg portions is necessary in assembling the spring clips in the inclined recesses 35. It is apparent, therefore, that this method of assembling the keys in a key container will be simpler than many previous methods which often required considerable force in assembling.

To separate the housing portions to remove and replace keys, it is simply necessary to remove the spring clips 13 and 14 and the keys are free to be removed without further manipulation. The springs 28 and 29 are shown with an end portion 46 merely resting in a slot 31 and with the other end 47 engaging an intermediate shank portion 30. The spring in this position would be preferably

under a slight compression with the stud in its furthest rearward position so that the spring would tend to remain in the housing portion even though the housing portions were separated and inverted.

Attention is called to the fact that the diameters of disk 23 and flange 27 are slightly less than the diameter of the bayonet portion 38 of each slot. Hence during factory assembly the inner end of each stud may be inserted through such bayonet portion, after which the spring end 47 engaged between flange 27 and disk 23 effectively prevents accidental escape of the stud from its slot.

The key container of my invention is preferably made of a plastic and may have incorporated therein phosphorescent material distributed over the entire container for illuminating a lock when there is otherwise insufficient illumination. Alternately the surfaces adjacent the opening 15 might be coated with a phosphorescent material or a pair of capsules of calcium sulfide or other phosphorescent material might be so placed.

Alternately the springs, of course, may be arranged, for example, to be in greatest tension when the keys are in the retracted position, and the bayonet slots may be arranged to hold the keys in retracted position against this tension. It will be appreciated that the key handle opening 25 usually would be of sufficient size to permit lateral movement of the studs for locking thereof in a bayonet slot, even when the key is in retracted position, without material alteration of my key housing. Additional keys could, of course, be carried in my key container either by increasing the length of the studs or by increasing the width of the container so that it might contain another housing somewhat similar to the one shown. The container could be made square, for instance, and have a key adapted to project from either end thereof if such were desired.

Any means well known in the art might be used for identifying the two housing portions so that their associated keys could be readily selectively employed, as for instance, by altering the configuration of one of the buttons, or placing some sort of a slot or groove on one surface of one of the housing portions.

It will, of course, be understood that the details of construction may be varied throughout a wide range without departing from the principles of this invention, and it is, therefore, not the purpose to limit the patent granted hereon otherwise than necessitated by the scope of the appended claims.

I claim as my invention:

1. A key container comprising a housing consisting of two opposed separable housing members and means for releasably securing them together, each member having a narrow longitudinal slot in its outer side wall and a key projection slot in one of its end edge walls, a key manipulating stud for each member having an enlarged outer head overlying and slidably on the side margins of said longitudinal slot, a shank of said stud extending inwardly through said slot and having guide means thereon engaging the inner marginal surfaces of said slot, a further inward projection of said stud being adapted for entering the handle aperture of a key for propelling the same, a zigzag shaped wire spring lying in a flat plane associated with each stud and having one end anchored in said housing member adjoining said key projection slot,

the other end of said spring being operatively connected with said stud under compression and held against displacement longitudinally of the stud, and a ledge on each housing member adjoining said key projection slot slidably engageable by the shank of a key for spacing such key somewhat inwardly from the inner surface of the housing wall providing thereby clearance space for the movement of said spring.

2. A key container comprising a housing consisting of two opposed separable housing members and means for releasably securing them together, each member having a narrow longitudinal slot in its outer side wall and a key projection slot in one of its end edge walls, a key manipulating stud for each member having an enlarged outer head overlying the side margins of said longitudinal slot on the outer side of said member, a shank on each said stud extending inwardly through said slot from said head, a pair of closely spaced flanges on said stud inside said housing and overlying the side margins of said longitudinal slot, a further inward projection of said stud being adapted for entering the handle aperture of a key for propelling the same, a zigzag shaped wire spring for each stud having one end thereof anchored in the associated housing member adjoining said key projection slot and having its other end engaged with the stud under compression between said flanges, each housing member having a laterally offset slot connected with its longitudinal slot near that end thereof which adjoins said key projection slot, whereby either of two keys when associated in propellable relation with said studs may be selectively projected partially from said housing against the compression of its associated spring into operative position and held projected by movement of its associated stud into said offset slot and returned by reverse movement and held in fully retracted position within the housing by expansion of its spring.

3. A key container comprising a housing consisting of two opposed separable housing members and means for releasably securing them together, each member having a narrow longitudinal slot in its outer side wall and a key projection slot in one of its end edge walls, a key manipulating stud for each member having an enlarged outer head overlying the side margins of said longitudinal slot on the outer side of said member, a shank on each said stud extending inwardly through said slot from said head, a pair of closely spaced flanges on said stud inside said housing and overlying the side margins of said longitudinal slot, a further inward projection of said stud being adapted for entering the handle aperture of a key for propelling the same, a zigzag shaped wire spring for each stud having one end thereof anchored in the associated housing member adjoining said key projection slot and having its other end engaged with the stud under compression between said flanges, each housing member having a laterally offset slot connected with its longitudinal slot near that end thereof which adjoins said key projection slot, whereby either of two keys when associated in propellable relation with said studs may be selectively projected partially from said housing against the compression of its associated spring into operative position and held projected by movement of its associated stud into said offset slot and returned by reverse movement and held in fully retracted position within the housing by expansion of its spring, each housing member

having an inwardly extending ledge adjoining its key projection slot for engagement with the side of a key shank to hold the latter spaced inwardly slightly from the plane of the associated spring.

4. A key container comprising a housing consisting of two opposed separable housing members and means for releasably securing them together, each member having a narrow longitudinal slot in its outer side wall and a key projection slot in one of its end edge walls, a key manipulating stud for each member having an enlarged outer head overlying the side margins of said longitudinal slot on the outer side of said member, a shank on each said stud extending inwardly through said slot from said head, a pair of closely spaced flanges on said stud inside said housing and overlying the side margins of said longitudinal slot, a further inward projection of said stud being adapted for entering the handle aperture of a key for propelling the same, a zigzag shaped wire spring for each stud having one end thereof anchored in the associated housing member adjoining said key projection slot and having its other end engaged with the stud under compression between said flanges, each housing member having a laterally offset slot connected with its longitudinal slot near that end thereof which adjoins said key projection slot, whereby either of two keys when associated in propellable relation with said studs may be selectively projected partially from said housing.
